UNITED STATES PATENT OFFICE.

DAVID G. WHERRY, OF LOS ANGELES, CALIFORNIA.

PUMP.

1,238,467.

Specification of Letters Patent.

Patented Aug. 28, 1917.

Application filed May 5, 1916. Serial No. 95,608.

To all whom it may concern:

Be it known that I, DAVID G. WHERRY, a citizen of the United States, residing in Los Angeles, in the county of Los Angeles and 5 State of California, have invented new and useful Improvements in Pumps, of which the following is a specification.

This invention has reference to an organization of movable elements which are capable, under the pressure of a fluid medium, 10 of furnishing power, and which are capable, on the application of power thereto, of moving or lifting a fluid medium, as in the pumping of water, or of pumping air for 15 the purpose of compression or for the various uses for which the compressed air may be employed.

The objects of the invention are, to accomplish the movement of a fluid medium 20 of largest possible volume, combined with continuity of impulse and least expenditure of mechanical energy, and to provide mechanism with movable elements that may be driven in either direction for pumping purposes.

Other objects and advantages may appear from the subjoined detail description.

In the drawings—Figure 1 is an elevational section with receding parts in perspective, of a pump incorporating the principles of this invention. Fig. 2 is a side elevation of the pump. Fig. 3 is a perspective detail of a rotary abutment. Fig. 4 is a side elevation of the primary rotor. Fig. 35 5 is an elevation of the inner side of the casing, and shows one of the slide valves which controls the admission of water to the piston chamber. Fig. 6 is a side elevation of the fluid medium distributing plate, 40 showing the four slide valves, the rotor being shown back of the plate in dotted lines. Fig. 7 is a plan section on the line X' of Fig. 2.

Referring to the drawing, the rotative 45 and operative elements referred to are mounted in a suitable casing 1, having the outer end walls 2, 3, which are provided with intake and exhaust ports or openings 4, 5, respectively, connecting with intake and exhaust chests, 10, 11, respectively. The shaft 6 is journaled in the end walls 2, 3, and has mounted thereon the rotor 7 and the pulley 8. When used as a pump, the pulley 8 is the driving member, and the 50 rotor 7, the driven member. The rotor 7 is

provided with a series of radial vanes 9 which serve as force and suction elements.

Slide valves 13, 14, 15, 16, are provided with studs 17, projecting into groove 12, in end wall 27, of the rotor; said studs being 60 provided with rollers 18, working in slots 20, in plate 19, and actuating the valves to open and close ports 21, 22, 23, 24.

A series of intermittently rotating abutments 25, are provided and divide the space 65 between the outer wall 26, of the rotor and the wall of the casing 1, into a series of contiguously-arranged chambers, each of said chambers having the intake port at one corner, and the exhaust port at the diagonally opposite corner.

Assuming the device to be used as a pump, the water enters the intake chest 10, and from thence is drawn through the ports 21, 22, 23, 24, through the suction created 75 by the vacuum made by the vanes 9 as they pass the intake ports and recede from the abutments 25. The water thus drawn in by one of said vanes is forced out and into the exhaust chest 11, by the next successive 80 vane. The water thus has a practically continuous movement through the device. Three vanes are shown but any number of vanes may be used, and the force or velocity 85 of water projected by one vane will be blended with the impulse that is created by the next successive vane. In installing the device for use, the exhaust pipe (not shown) may be provided with a check valve (not shown) to prevent any back pressure of the 90 water.

Abutments 25, which divide the annular space within the casing into a series of compartments, have an intermittent rotary motion to allow the vanes 9 to travel from one 95 compartment to another. Each slide valve is in closed position while the vane is passing the corresponding intermittent rotary abutment.

From the foregoing it may be seen that 100 the invention comprehends an organization of movable elements, operable through independent paths, but each element interdependent upon the other for its movement, and the combination of which is capable of 105 pumping water or air, or producing power. Certain of the elements are interdependent upon the others for the regulation of the power of the medium by which the others are operated. The intermittent rotary ele- 110

ments are supported by the pressure of the power producing medium thereupon, whereby the resistance upon the rotor is reduced to a minimum. The impact sustaining elements upon the rotor vary in number with the impact chambers, whereby the initial force from one chamber will be counterbalanced by the failing force in the others.

The primary object of the invention is to 10 provide a simple and efficient mechanism for pumping purposes, capable of moving or handling a large volume of water, or compressing or driving a maximum quantity of air, with a minimum expenditure of mechanical power, and capable, as a motor, of 15 translating fluid medium pressure into mechanical energy.

While the elements shown and described are well adapted to serve the purposes for 20 which they are intended, it is to be understood that the invention is not limited to the precise construction shown, but minor changes and modifications which may fall within the scope of the appended claims, 25 may be made.

What is claimed is:

1. A pump casing having an intake chest, an exhaust chest, an intermediate piston chamber, a rotary piston in the intermediate 30 chamber, spaced apart from the casing wall, intermittently actuated rotary abutments dividing the inclosed space into compartments, and oscillating slide valves actuated by the piston to open and close communication between the piston chamber and intake 35 and exhaust chests.

2. A pump comprising a casing, a rotor within the casing, the rotor being spaced apart from the wall of the casing, rotary 40 abutments dividing the space between the periphery of the rotor and the wall of the casing into a series of contiguous compartments, intake and exhaust chests adjoining the rotor chamber, ports of communication 45 between said intake and exhaust chests and said compartments, whereby the transition of water is effected, and valve means for opening and closing said ports.

3. In a pump, the combination with a casing having chambers and ports leading from one to another of said chambers, of a rotor in one chamber, oscillating members in another of said chambers to open and close said

ports, and means to actuate the oscillating members to open and closed positions.

55

4. In a pump, the combination with a rotor having a grooved end wall, of a casing for the rotor, slide valve members in continual contact with the grooved end wall, vanes on the rotor, and intermittent rotary 60 abutments forming compartments within the casing and adjacent to the rotor, said slide valve members having an intermittent oscillating motion to admit fluid or air medium within the compartments.

65

5. In a pump, the combination with a series of fixed fulcrum angularly-movable valve members, of a rotary piston for effecting the movement of said valve members.

6. In a pump, the combination with a 70 rotary piston and a casing having ports therein, of a series of pivoted slide valves having an angular movement in unison with the movement of the piston to control said ports.

75

7. In a pump, the combination with a casing, of a rotary piston within the casing, the periphery of the piston being spaced apart from the wall of the casing to form an annular chamber, suction and force vanes extending radially from the periphery of the piston, intermittently actuated rotary abutments dividing the annular chamber into a series of contiguous compartments, varying in number from the piston vanes, said compartments having inlet and discharge ports, and means actuated by the movement of the piston to open and close said ports.

80

8. In a pump, the combination with a casing, said casing having chambers and ports of communication between adjoining chambers, of a series of fixed fulcrum angularly movable valve members to open and close said ports, a rotary piston within the casing, having a groove in one end thereof, and a stud on each of said angularly movable valve members, engaging with said groove whereby the valve members are actuated in unison to successively open and close said ports as the piston is rotated.

85

9. In testimony whereof, I hereunto affix my signature, on the 29th day of April, in the year 1916.

95

100 DAVID G. WHERRY.

In presence of—
FREDERIC M. KEENENY.
